(57) **CLAIM**

The ornamental design for a light fixture, as shown and described.

DESCRIPTION

FIG. 1 is a front perspective view of an embodiment of a light fixture showing my new design;

FIG. 2 is a right side elevational view thereof, the left side being a mirror image;

FIG. 3 is a top plan view thereof;

FIG. 4 is a front side elevational view thereof, the rear side being a mirror image;

FIG. 5 is a bottom plan view thereof;

FIG. 6 is a front perspective view of a second embodiment of a light fixture;

FIG. 7 is a right side elevational view thereof, the left side being a mirror image;

FIG. 8 is a front side elevational view thereof, the rear side being a mirror image;

FIG. 9 is a top plan view thereof; and,

FIG. 10 is a bottom plan view thereof.

The broken lines in the drawings illustrate portions of the light fixture and form no part of the claimed design.

The break lines in the drawings indicate that the appearance of any portion of the light fixture between the break lines forms no part of the claimed design.
